CLAIM

The ornamental design for a washbasin, as shown and described.

DESCRIPTION

Fig. 1.1 is a front elevation view showing our new design; Fig. 1.2 is a rear elevation view thereof; Fig. 1.3 is a left side elevation view thereof; Fig. 1.4 is a right side elevation view thereof; Fig. 1.5 is a top plan view thereof; and Fig. 1.6 is a top perspective view thereof.

The broken lines depict features of the washbasin that form no part of the claimed design.
